CLARK L. TYLER, OF ITHACA, NEW YORK.

Letters Patent No. 96,366, dated November 2, 1869.

IMPROVEMENT IN PENCIL-ATTACHMENT TO COMPASSES.

The Schedule referred to in these Letters Patent and making part of the same.

To all whom it may concern:

Be it known that I, CLARK L. TYLER, of Ithaca, Tompkins county, New York, have invented an Improvement in Attaching Pencils to Dividers, of which the following is a specification.

My object is to make a holder which shall be self-adjustable to the pencil, and also to the leg of the dividers.

Figure 1 is a side view of my pencil-holder;

Figure 2, a section thereof;

Figure 3, a view of the internal variable block; and

Figure 4, sections of this block, and its axis.

In fig. 1, A and B are two tubes, one for the pencil and the other for one leg of the dividers, connected by the part C, which is a double web, between the tubes, as is more clearly seen in fig. 2.

Fig. 3 is a side elevation of the two-parted block or variable frame, between the pencil and the leg of the dividers, which variable block is composed of the parts D and E, with the pin or axis G', joining them. In fig. 4, the axis of the two parts of the block is more clearly seen.

It is evident, that when the variable block is put in the web between the two tubes, and secured by the

pin in the slot G", fig. 1, a pencil put in one of the tubes will bear on one of the parts of the block; and when the leg of the dividers is thrust into the other tube, the thrusting in causes the variable block to act, and to hold both pencil and dividers; the oscillation of one of the said parts of the block, allowing an adjustment to the varying taper of the compass-leg, and the lateral play of the compound block, by its axis in the transverse slot, allowing its adjustment to different-sized pencils.

The uses and advantages of my invention are apparent to those skilled in the art to which it appertains.

Claim.

The combination and arrangement of the double-tubed socket A B, united by the open web C, with the variable block or frame, formed of the two parts D and E jointed together, the pin or axis of which plays in the transverse slot G" of the said web C, substantially as described.

CLARK L. TYLER.
